SIGNAL DEVICE

Wallace J. Wolf, Rochester, N. Y., assignor to
 Bastian Brothers Company, Rochester, N. Y., a
 corporation of New York

Application June 24, 1937, Serial No. 150,192

2 Claims. (Cl. 88—80)

The present invention relates generally to signal devices and more particularly to signal devices of the general nature adapted to be carried upon the person, bearing in mind the present danger to which pedestrians are constantly subjected in walking along and across streets and roadways, parallel with and at right angles to vehicular traffic. It is a well known fact that many more or less fatal and certainly painful and unfortunate accidents constantly occur, especially during the night season, by reason of the presence of pedestrians on roadways and streets walking with or against, and crossing vehicular traffic, due to the fact that even with the efficient headlights with which vehicles are equipped, it often happens that a pedestrian appears within the effective view of the motorist only at the last minute when it is too late to avoid an accident. Many proposals have been made with the object of offsetting these disadvantages and preventing such accidents and among these proposals it is probable the most frequent have been the use of reflective signal members or devices to be carried by the pedestrian. There are however certain disadvantages to the use of such signals and up to the present at least it has been found difficult to overcome the disadvantage that the ordinary reflective signals either require the use of the hands of the pedestrian when the hands are needed for other purposes or are so positioned on the pedestrian that any substantial change in his direction of movement obscures the signal devices from view.

It is therefore one of the primary objects of this invention to provide a simple and inexpensive signal device capable of being carried in the pocket when not in use, and easily and quickly placed and adjusted in effective position where its use is desirable.

A further object is the provision of such a device which is at the same time readily shiftable upon the person of the user to easily and conveniently assume different positions wherein it will be similarly effective when the user is walking either parallel with, or at right angles to, vehicular traffic.

A still further object is the provision of a simple, cheap and effective device in which a pair of reflective signal elements may be employed to drape on the person in any manner adapting the same to effective use, and may be placed or displaced with ease and facility with provision for easy adjustment to persons of different sizes.

In the accompanying drawing which illustrates

the present invention and forms a part of the specification—

Figure 1 is a side view showing the practical application of the invention as it will be used on a pedestrian proceeding parallel to vehicular traffic. 5

Figure 2 is a front view showing the improved signal device as it will be used on a pedestrian proceeding at right angles to commercial traffic.

Figure 3 is a view showing possible use of the 10 signal device in the hand.

Figure 4 is a detail perspective view of the improved signal device removed.

Figure 5 is a detail view of one of the signal elements looking at its obverse face, and 15

Figure 6 is a detail vertical sectional view taken through one of the signal devices substantially on line 6—6 of Figure 5, and somewhat enlarged.

Referring now to these figures, the invention proposes a signal device, the essentials of which are a pair of signal members 10 and 11 which may be of identical form, and which are supported in substantially spaced apart and relatively adjustable relation by a flexible strand 12, so that they may be draped across the shoulders of a 20 user of the device and suspended at the chest and back of the latter when proceeding parallel to vehicular traffic as indicated in Figure 1 or at the upper portions of the arms when proceeding at right angles to vehicular traffic as indicated 25 in Figure 2.

Obviously the signal elements in the position of Figure 1 will show both to the front and the rear of the user while as positioned in Figure 2 they will be shown at both sides of the user. 35

For the above purposes the strand 12, which may for convenience and comfort be of the nature of a narrow substantially flexible tape and the like, is of endless form so that it constitutes a flexible supporting loop for the two signal elements, which loop may be readily passed downwardly over the head of the user so that portions of the loop engage the shoulders in either of the above described positions whereby the two signal elements are conveniently and comfortably displayed without necessitating the use of the hands other than to place and displace the same or shift them from one position to the other in the event the direction in which the user is proceeding is changed with respect to the direction of vehicular 40 traffic. 45

Each of the signal elements 10 and 11 preferably consists of a reflective signal disk 13 having a shouldered peripheral portion 14 engaged in overlapping relation by the inner edge of a flat 50 55

5 confining ring 15. The other peripheral edge of this ring 15 is overlapped by the forwardly flanged peripheral edge 16 of a back plate 17 which may be either used of and by itself or in connection with an overlying facing 18 of colored Celluloid or transparent Celluloid or equivalent material over a printed label.

10 The ring 15 which serves to confine the signal disk 13 against the back plate 17 is preferably provided with a pair of adjacently located apertures 19 and through these apertures the strand 12 of the flexible supporting loop is loosely extended so that the two signal elements are thus movable on the strand relative to one another 15 around the loop. Obviously then the loop may be made in the first instance to conveniently support the two signal elements in the manner previously described, upon a person of maximum proportions and if there is necessity for adjustment to properly and conveniently fit a smaller person, the strand 12 forming the loop may be reduced in length by tying in a portion thereof and then by shifting one of the signal members on the strand relative to the other the two signal 20 members may be easily and quickly repositioned at diametrically opposite points of the loop of reduced circumference.

25 Since the two signal elements of the above construction may be formed quite thin and substantially flat and since they are connected merely by means of a flexible member, they may in use be placed back to back and by wrapping the flexible supporting connection thereof around them, they may be held in connection with one 30 another in such position against danger of displacement and at the same time a conveniently small bundle is formed capable of being readily carried in the pocket, the wrapping of the flexible supporting member therearound serving the additional function of protecting the outwardly 35 facing signal disks 13 from scratching and marring against other objects in the pocket.

40 Obviously also in some instances, wherever necessary or desirable, the signal elements may be carried in the hand by placing the same in 45 back to back relation and grasping the flexible

connecting strand 12 in the hands as shown in Figure 3, to serve a further function such for instance as a movable signal capable of use if it is desired to signal the stopping of a vehicle for example a taxicab.

5 What is claimed is:—

1. A signal device comprising a pair of signal supporting elements, a pair of reflective signal disks, each of said supporting elements having a portion at the front face thereof engaging and holding its respective signal disk, and a supporting connection for said elements consisting of an endless flexible strand in the form of a loop adapted to be extended downwardly over the head of the user and draped across the user's 15 shoulders, said supporting connection consisting of a light, flexible material and being also adapted to be carried in the hand and to be effectively reduced in circumference by tying in selective lengths thereof, the said strand being threaded 20 loosely through apertures formed in the said front disk-holding portions of the supporting elements whereby the said elements may be disposed diametrically opposite one another on the loop and will present unobstructed rear surfaces 25 for disposal against the chest and back or upper arms of the user for effective positioning when the user is walking parallel with or at right angles to, vehicular traffic.

2. A signal device comprising an endless flexible strand forming a loop adapted to be extended downwardly over the head of the user and to be draped across the user's shoulders, and a pair of signal supporting elements, each consisting of a generally flat frame having front and rear 30 walls, and a reflective signal disk mounted in the front wall of the frame, each frame presenting a smooth unobstructed rear surface and having adjacently located openings in its front wall at a point between its signal disk and the edge of 35 the frame, through which the said strand forming the loop is loosely threaded to permit shifting of the signal supporting elements around the loop.
